(57) **ABSTRACT**

A vane pump includes: pump chambers formed by a rotor, a cam ring, and vanes; a first suction port that guides working fluid guided by a suction passage to the pump chambers; a second suction port that guides the working fluid guided from the suction passage through a communication passage to the pump chambers; and a return passage to which excessive fluid of the working fluid discharged from the pump chambers is guided. The return passage has: a body-internal passage through which the excessive fluid flows along an axis direction at an outer side of the cam ring in a radial direction; and a turning passage that reverses the excessive fluid guided through the body-internal passage towards the second suction port.

VANE PUMP

TECHNICAL FIELD

The present invention relates to a vane pump.

BACKGROUND ART

There is a known vane pump in which a part of working oil (excessive oil) discharged from pump chambers is recycled to the pump chambers (see JP2014-126043A). In the vane pump described in JP2014-126043A, an inlet provided in a pump housing is in direct communication with a sub-suction port from a sub-suction oil passage provided in the pump housing and is in communication with a main suction port from a main suction oil passage through an outer circumference oil passage provided around a cam ring in the pump housing.

In addition, in the vane pump described in JP2014-126043A, a return oil passage, which is branched from a switching valve provided in a sub-discharge oil passage communicating with a sub-discharge port of the sub-pump chamber, is provided as a recycling configuration of the excessive oil in a cover, and the return oil passage is made to communicate with the main suction port of a main pump chamber via the main suction oil passage provided in the pump housing. Therefore, the excessive oil discharged from the sub-discharge port is recycled to the main suction port via the return oil passage.

SUMMARY OF INVENTION

With the vane pump described in JP2014-126043A, the excessive oil that has been guided to the return oil passage flows into the main suction port and also flows into the outer circumference oil passage. The direction of the flow of the excessive oil being guided to the outer circumference oil passage is opposite from that of the flow of the working oil flowing from the inlet towards the main suction port through the outer circumference oil passage. Therefore, there is a concern that the flow of the working oil being sucked into the main suction port and the sub-suction port from the inlet is inhibited by the excessive oil, and a suction property of the vane pump is deteriorated.

An object of the present invention is to improve a suction property of a vane pump.

According to one aspect of the present invention, a vane pump includes: a rotor configured to be rotationally driven; a plurality of vanes provided so as to be capable of freely reciprocating in a radial direction with respect to the rotor; a cam ring having an inner circumference cam face on which tip end portions of the plurality of vanes slide with rotation of the rotor; a body having an accommodating portion for accommodating the rotor and the cam ring; a cover attached to the body to close the accommodating portion; pump chambers formed by the rotor, the cam ring, and the adjacent vanes; a first suction port configured to guide working fluid to the pump chambers, the working fluid being guided by a suction passage provided in the body; a second suction port configured to guide the working fluid to the pump chambers, the working fluid being guided from the suction passage through a communication passage provided in the cover or the body; and a return passage to which excessive fluid is guided, the excessive fluid being derived from the working fluid discharged from the pump chambers. The return passage has: an axial direction passage through which the excessive fluid flows along a rotation-axis direction of the

rotor at an outer side of the cam ring in a radial direction; and a turning passage configured to reverse the excessive fluid towards the second suction port, the excessive fluid being guided through the axial direction passage.

2

BRIEF DESCRIPTION OF DRAWINGS

FIG. 1 is a sectional view of a vane pump according to an embodiment of the present invention.

10 FIG. 2 is a diagram showing an internal structure of the vane pump and shows a state in which a cover and a cover-side side plate are removed.

FIG. 3 is a front view of a body-side side plate, viewed from a cam ring side.

15 FIG. 4 is a perspective view of a cover and the cover-side side plate.

FIG. 5 is a perspective view of a cartridge.

20 FIG. 6 is a plan view of the cover and the cover-side side plate, viewed from the VI direction in FIG. 4, and shows a flow of working oil (a main flow) guided from a suction passage to a communication passage and the flow of the working oil (a returning flow) flowing through a return passage.

25 FIG. 7A is a schematic side-sectional view of the vane pump according to this embodiment and shows the flow of the working oil (the main flow) guided from the suction passage to the cartridge and the flow of the working oil (the returning flow) guided from the return passage to the cartridge.

30 FIG. 7B is the schematic side-sectional view of the vane pump according to a comparative example of this embodiment and shows the flow of the working oil (the main flow) guided from the suction passage to the cartridge and the flow of the working oil (the returning flow) guided from the return passage to the cartridge.

35 FIG. 8 is the schematic side-sectional view of the vane pump according to a first modification of this embodiment and shows the flow of the working oil (the main flow) guided from the suction passage to the cartridge and the flow of the working oil (the returning flow) guided from the return passage to the cartridge.

40 FIG. 9 is the schematic side-sectional view of the vane pump according to a second modification of this embodiment and shows the flow of the working oil (the main flow) guided from the suction passage to the cartridge and the flow of the working oil (the returning flow) guided from the return passage to the cartridge.

45 FIG. 10 is the schematic side-sectional view of the vane pump according to a third modification of this embodiment and shows the flow of the working oil (the main flow) guided from the suction passage to the cartridge and the flow of the working oil (the returning flow) guided from the return passage to the cartridge.

55 DESCRIPTION OF EMBODIMENTS

A vane pump according to an embodiment of the present invention will be described below with reference to the drawings. The vane pump is used as a fluid pressure source for a fluid hydraulic apparatus mounted on a vehicle, such as a power steering apparatus, a transmission, and so forth. Although a description is given to the vane pump using working oil as working fluid in this description, other fluid such as working water, etc. may also be used as the working fluid.

60 FIG. 1 is a sectional view of a vane pump 100. FIG. 2 is a diagram showing an internal structure of the vane pump

100 and shows a state in which a cover 20 and a cover-side side plate 40 are removed. Here, FIG. 1 schematically shows a cross section taken along a line I-I shown in FIGS. 2 and 4.

As shown in FIGS. 1 and 2, the vane pump 100 is provided with: a pump cartridge (hereinafter, simply referred to as a cartridge) 9 that sucks the low-pressure working oil and discharges the high-pressure working oil; a body 10 that has an accommodating concave portion 10b serving as an accommodating portion accommodating the cartridge 9; the cover 20 that is attached to the body 10 to close an opening of the accommodating concave portion 10b; and a drive shaft 1 that is rotatably supported by the body 10 and the cover 20 via bearings 11 and 12.

The cartridge 9 is provided with: a rotor 2 that is rotationally driven by being linked to the drive shaft 1; a plurality of slits 2s that open at an outer circumferential surface of the rotor 2; a plurality of vanes 3 that are respectively received in the slits 2s of the rotor 2 in a freely slidable manner; a cam ring 4 that accommodates the rotor 2 and the vanes 3; and a pair of side members (a body-side side plate 30 and the cover-side side plate 40) that are arranged so as to sandwich the rotor 2 and the cam ring 4.

The vane pump 100 is driven by a driving device (not shown), such as an engine, an electric motor, and so forth, and thereby, the rotor 2 linked to the drive shaft 1 is rotationally driven in the clockwise direction as shown by an arrow A in FIG. 2 to generate the fluid pressure.

In the following, the direction extending along an rotation center axis O of the rotor 2 will be referred to as "the axial direction", the radiating direction centered at the rotation center axis O of the rotor 2 will be referred to as "the radial direction", and the rotating direction of the rotor 2 when the vane pump 100 is operated will be referred to as "the rotation direction".

As shown in FIG. 1, the body-side side plate 30 is a disc-shaped member arranged between a bottom surface of the accommodating concave portion 10b and the cam ring 4, and one end surface of the rotor 2 in the axial direction (the right side surface in the figure) comes into sliding contact with the body-side side plate 30 and the one end surface of the cam ring 4 in the axial direction comes into contact with the body-side side plate 30.

The cover-side side plate 40 is a disc-shaped member arranged between the cover 20 and the cam ring 4, and other end surface of the rotor 2 in the axial direction (the left side surface in the figure) comes into sliding contact with the cover-side side plate 40 and the other end surface of the cam ring 4 in the axial direction comes into contact with the cover-side side plate 40. The cover-side side plate 40 is a plate member arranged between a communication passage 102, which will be described below, and pump chambers 6.

As described above, the body-side side plate 30 and the cover-side side plate 40 are arranged so as to respectively face both end surfaces of the rotor 2 and the cam ring 4 in the axial direction. In other words, the body-side side plate 30 and the cover-side side plate 40 are arranged so as to sandwich the rotor 2 and the cam ring 4 in the axial direction.

The rotor 2, the plurality of vanes 3, the cam ring 4, the cover-side side plate 40, and the body-side side plate 30 are assembled as the cartridge 9, and the cartridge 9 is accommodated in the accommodating concave portion 10b of the body 10. In this state, by attaching the cover 20 to the body 10, the accommodating concave portion 10b is closed.

As shown in FIG. 2, the plurality of the slits 2s are formed in the rotor 2 in a radiating pattern. The slits 2s respectively

have opening portions 2a at the outer circumference of the rotor 2. The opening portions 2a of the slits 2s are respectively formed at raised portions 23 that protrude from the outer circumference of the rotor 2 outwards in the radial direction. In other words, the raised portions 23 are formed on the outer circumference of the rotor 2 such that the number thereof corresponds to that of the slits 2s. Each of the raised portions 23 supports the vane 3 on the front and back sides in the rotation direction.

10 The vanes 3 are provided so as to be capable of reciprocating in a radial direction with respect to the rotor 2. Each of the vanes 3 has a rectangular flat plate shape and is inserted into the slit 2s so as to be freely slidable. Each of the vanes 3 has a tip end portion 3a that is an end portion in the direction projecting out from the slit 2s and a base-end portion 3b that is an end portion at the opposite side of the tip end portion 3a. In the slits 2s, back pressure chambers 5 are respectively formed on the bottom portion side of the slits 2s and the base-end portions 3b of the vanes 3. The back pressure chambers 5 are in communication with discharge ports 31, which will be described later, and the high-pressure working oil is guided to the back pressure chambers 5 from the discharge ports 31. The vanes 3 are pushed by pressure in the back pressure chambers 5 in the direction in which the vanes 3 project out from the slits 2s.

15 The cam ring 4 is an annular member having an inner circumference cam face 4a serving as an inner circumferential surface having a substantially oval shape and pin holes 4b through which positioning pins 8 are inserted. The inner circumference cam face 4a is a surface on which the tip end portions 3a of the plurality of vanes 3 slide along with the rotation of the rotor 2.

20 As the rotor 2 is rotated, a centrifugal force acts on the vanes 3. The vanes 3 are biased by this centrifugal force in the directions in which the vanes 3 project out from the slits 2s. In other words, the vanes 3 are biased in the directions (outwards in the radial direction) in which the vanes 3 project out from the slits 2s by the fluid pressure in the back pressure chambers 5 pushing the base-end portions 3b and the centrifugal force generated due to rotation of the rotor 2. As the vanes 3 are biased outwards in the radial direction, the tip end portions 3a of the vanes 3 are brought into sliding contact with the inner circumference cam face 4a of the cam ring 4. Thereby, in the cam ring 4, the pump chambers 6 are formed by the outer circumferential surface of the rotor 2, the inner circumference cam face 4a of the cam ring 4, the adjacent vanes 3, the body-side side plate 30, and the cover-side side plate 40.

25 Because the inner circumference cam face 4a of the cam ring 4 has the substantially oval shape, as the rotor 2 is rotated, the displacement of each of the pump chambers 6, which are defined by the respective vanes 3 in sliding contact with the inner circumference cam face 4a, is repeatedly expanded and contracted. The working oil is sucked into the pump chambers 6 in an expansion region (suction region) where the pump chambers 6 are expanded, and the working oil is discharged from the pump chambers 6 in a contraction region (discharge region) where the pump chambers 6 are contracted.

30 The vane pump 100 according to this embodiment has a first suction region 82a and a first discharge region 82b in which the vanes 3 undergo a first reciprocating movement and a second suction region 82c and a second discharge region 82d in which the vanes 3 undergo a second reciprocating movement. While the rotor 2 completes a full rotation, the pump chambers 6 are expanded in the first suction

region **82a**, contracted in the first discharge region **82b**, expanded in the second suction region **82c**, and contracted in the second discharge region **82d**. Although the vane pump **100** according to this embodiment has two suction regions **82a** and **82c** and two discharge regions **82b** and **82d**, the configuration is not limited thereto, and the vane pump **100** may have a configuration in which three or more suction regions and three or more discharge regions are provided.

As shown in FIG. 1, the vane pump **100** is further provided with: a suction passage **101** that is connected to a tank **60** and guides the working oil stored in the tank **60** to the pump chambers **6** positioned in the suction regions **82a** and **82c**; a discharge passage (not shown) that guides the working oil that has been discharged from the pump chambers **6** positioned in the discharge regions **82b** and **82d**; and a return passage **120** through which excessive oil (excessive fluid) that is a part of the working oil that has been discharged from the pump chambers **6** positioned in the discharge regions **82b** and **82d** is guided.

An annular high-pressure chamber **14** is formed by the body **10** and the body-side side plate **30** on the bottom surface side of the accommodating concave portion **10b** of the body **10**. The high-pressure chamber **14** is connected to an external fluid hydraulic apparatus **70** (for example, a power steering apparatus, a transmission, and so forth) of the vane pump **100** via a discharge passage **62**.

The working oil that has been guided to the suction passage **101** provided in the body **10** is then sucked into the pump chambers **6** through a first suction port **91** and a second suction port **92** of the cartridge **9**. Details of the first suction port **91** and the second suction port **92** will be described later.

As shown in FIGS. 1 and 2, a first introduction concave portion **13a** that is connected to an end portion of the suction passage **101** at the exit side of the working oil is formed at the position of the body **10** corresponding to the first suction port **91** of the cartridge **9**. A second introduction concave portion **13b** that is connected to an end portion of the return passage **120** at the exit side of the working oil is formed at the position of the body **10** corresponding to the second suction port **92** of the cartridge **9**. The first introduction concave portion **13a** and the second introduction concave portion **13b** are respectively provided at the positions opposed to each other such that the cam ring **4** is located therebetween.

As shown in FIG. 1, the communication passage **102** that is in communication with the suction passage **101** is provided in the cover **20**. The cartridge **9** is assembled into the accommodating concave portion **10b** such that the first suction port **91** is positioned at the end portion of the suction passage **101** and such that the second suction port **92** is positioned at the end portion (the upper end portion in the figure) of the communication passage **102**.

As shown in FIGS. 1 and 2, in the cam ring **4**, cut-out portions **4c** and **4d** are provided so as to penetrate from the outer circumferential surface of the cam ring **4** to the inner circumference cam face **4a**. One cut-out portions **4c** each opens at the axial direction end surface that is in contact with the body-side side plate **30**, and the other cut-out portions **4d** each opens at the axial direction end surface that is in contact with the cover-side side plate **40**.

In other words, the cam ring **4** has wide-width portions **4e** (see FIG. 5) that are each in contact with the body-side side plate **30** and the cover-side side plate **40** and narrow-width portions **4f** (see FIG. 5) that are each not in contact with the body-side side plate **30** and the cover-side side plate **40**. The

cut-out portions **4c** and **4d** are respectively provided on both sides of the narrow-width portions **4f** in the axial direction.

FIG. 3 is a front view of the body-side side plate **30**, viewed from the cam ring **4** side. As shown in FIG. 3, the body-side side plate **30** is a circular plate-like member. The body-side side plate **30** has: a sliding surface **30a** including a region on which the end surfaces of the vanes **3** in the axial direction slide; a through hole **32** through which the drive shaft **1** is inserted; the discharge ports **31** that are formed so as to respectively correspond to the first discharge region **82b** and the second discharge region **82d**; recessed portions **33** that are formed so as to respectively correspond to the first suction region **82a** and the second suction region **82c**; and pin holes **39** through which the positioning pins **8** are respectively inserted.

The discharge ports **31** are provided at two positions opposed to each other such that the through hole **32** is located therebetween. The discharge ports **31** are each formed to have an arc shape centered at the through hole **32**.

Each of the discharge ports **31** penetrates through the body-side side plate **30** and communicates with the high-pressure chamber **14** that is formed in the body **10**. The discharge ports **31** guide the working oil that has been discharged from the pump chambers **6** to the high-pressure chamber **14**. The working oil that has entered the high-pressure chamber **14** is then supplied to the fluid hydraulic apparatus **70** outside the vane pump **100** through the discharge passage **62** (see FIG. 1).

The sliding surface **30a** of the body-side side plate **30** has a pair of back-pressure grooves **34** that are formed so as to oppose with each other such that the through hole **32** is located therebetween and a pair of back-pressure grooves **35** that are formed so as to oppose with each other such that the through hole **32** is located therebetween. The back-pressure grooves **34, 35** are each formed to have a groove shape that opens at the sliding surface **30a**. The back-pressure grooves **34, 35** are each formed to have an arc shape centered at the through hole **32** so as to communicate with the plurality of back pressure chambers **5** overlapping with the back-pressure grooves **34, 35**. In addition, the back-pressure grooves **34, 35** communicate with the high-pressure chamber **14**.

As shown in FIGS. 1 and 3, the recessed portions **33** are provided at two positions opposed to each other such that the through hole **32** is located therebetween. The recessed portions **33** are respectively formed at positions corresponding to the first introduction concave portion **13a** and the second introduction concave portion **13b** of the body **10**. The recessed portions **33** are each formed to have a recessed shape that opens at an outer circumferential surface of the body-side side plate **30** and an end surface of the body-side side plate **30** that is in contact with the cam ring **4**. An outer circumferential end of the recessed portions **33** reaches the outer circumferential surface of the body-side side plate **30**. The depth of the recessed portions **33**, in other words, the length of the recessed portions **33** in the axial direction from the end surface of the body-side side plate **30** that is in contact with the cam ring **4** to a bottom surface of the recessed portions **33** is smaller than the width (the thickness) of the body-side side plate **30**.

FIG. 4 is a perspective view showing the cover **20** and the cover-side side plate **40**. As shown in FIG. 4, the cover-side side plate **40** is a circular plate-like member having: a sliding surface **40a** including a region on which the end surfaces of the vanes **3** in the axial direction slide; a through hole **42** through which the drive shaft **1** is inserted; opposing grooves **41** that are formed so as to respectively correspond to the first discharge region **82b** and

the second discharge region **82d**; cut-out portions **43** that are formed so as to respectively correspond to the first suction region **82a** and the second suction region **82c**; and pin holes **49** through which the positioning pins **8** are respectively inserted. The cover-side side plate **40** is aligned with respect to the cam ring **4** and the body-side side plate **30** by the positioning pins **8**.

The opposing grooves **41** are each a groove formed to have an arc shape centered at the through hole **42** and are formed so as to respectively face the discharge ports **31** in the axial direction such that the vanes **3** and the pump chambers **6** are located therebetween. In other words, each of the opposing grooves **41** is in communication with each of the discharge ports **31** via the pump chambers **6**. Because the pressure acting on the opposing grooves **41** is the same as the pressure acting on the discharge ports **31**, the force acting on the vanes **3** by the pressure in the discharge ports **31** is cancelled out by the pressure in the opposing grooves **41**. Thus, it is possible to prevent the vanes **3** from being pushed against the cover-side side plate **40** by the pressure in the discharge ports **31**.

As shown in FIGS. 1 and 4, the sliding surface **40a** of the cover-side side plate **40** has a pair of back-pressure grooves **44** that are formed so as to oppose with each other such that the through hole **42** is located therebetween and a pair of back-pressure grooves **45** that are formed so as to oppose with each other such that the through hole **42** is located therebetween. The back-pressure grooves **44, 45** are each formed to have a groove shape that opens at the sliding surface **40a**. The back-pressure grooves **44, 45** are each formed to have an arc shape centered at the through hole **32** so as to communicate with the plurality of back pressure chambers **5** overlapping with the back-pressure grooves **44, 45**. The back-pressure grooves **44** communicate with the back-pressure grooves **45** via communication grooves. In addition, the back-pressure grooves **44, 45** communicate with the high-pressure chamber **14**.

The cut-out portions **43** are provided at two positions opposed to each other such that the through hole **42** is located therebetween. The cut-out portions **43** are respectively formed at positions corresponding to the first introduction concave portion **13a** and the second introduction concave portion **13b** of the body **10**. The cut-out portions **43** are each formed so as to open at an outer circumferential surface of the cover-side side plate **40** and so as to penetrate through between both end surfaces in the axial direction. The cut-out portions **43** are each formed across the entire width at a part of the cover-side side plate **40** along the circumferential direction so as to have a recessed shape that is recessed in the radial direction from the outside towards the inside.

FIG. 5 is a perspective view of the cartridge. As shown in FIGS. 1 and 5, in a state in which the body-side side plate **30** is assembled to the cam ring **4**, the recessed portions **33** of the body-side side plate **30** are arranged so as to be respectively adjacent to the cut-out portions **4c** of the cam ring **4**. Body-side side ports **51** of the cartridge **9** are formed by the recessed portions **33** of the body-side side plate **30** and the cut-out portions **4c** of the cam ring **4**.

As shown in FIGS. 1 and 5, in a state in which the cover-side side plate **40** is assembled to the cam ring **4**, the cut-out portions **43** of the cover-side side plate **40** are arranged so as to be respectively adjacent to the cut-out portions **4d** of the cam ring **4**. Cover-side side ports **52** of the cartridge **9** are formed by the cut-out portions **43** of the cover-side side plate **40** and the cut-out portions **4d** of the cam ring **4**.

The cartridge **9** has a pair of body-side side ports **51** and a pair of cover-side side ports **52**. Here, the body-side side port **51** and the cover-side side port **52** that are provided in the first suction region **82a** are referred to as the first suction port **91** of the cartridge **9**. In addition, the body-side side port **51** and the cover-side side port **52** that are provided in the second suction region **82c** are referred to as the second suction port **92**. In other words, the first suction port **91** has the body-side side port **51** and the cover-side side port **52** that are provided in the first suction region **82a**, and the second suction port **92** has the body-side side port **51** and the cover-side side port **52** that are provided in the second suction region **82c**.

The first suction port **91** guides the working oil that has been guided by the suction passage **101** to the pump chambers **6** positioned in the first suction region **82a**. The second suction port **92** guides the working oil that has been guided from the suction passage **101** via the communication passage **102** provided in the cover **20** to the pump chambers **6** positioned in the second suction region **82c**.

The return passage **120** will be described in detail with reference to FIG. 1. As shown in FIG. 1, the return passage **120** is connected to a flow-amount control valve **71** that controls a flow amount of the working oil supplied to the fluid hydraulic apparatus **70** via the discharge passage **62** by being discharged from the pump chamber **6**, and thereby, the return passage **120** guides the excessive oil that is not supplied to the fluid hydraulic apparatus **70** to the second introduction concave portion **13b**. The flow-amount control valve **71** may be provided outside the body **10** or may be provided in the body **10**.

The return passage **120** has a body-internal passage **121** serving as an axial direction passage provided in the body **10** and a turning passage **122** that is provided in the cover **20** so as to reverse the excessive oil that has been guided by the body-internal passage **121** towards the cover-side side port **52** of the second suction port **92** serving as a side port.

The body-internal passage **121** is formed so as to penetrate through the body **10** in a straight line along the axial direction on the outer side of the second introduction concave portion **13b** in the radial direction, in other words, on the outer side of the cam ring **4** in the radial direction. An inlet **120i** of the return passage **120** serving as an opening end of the body-internal passage **121** is formed at one end surface of the body **10** in the axial direction (the right-side end surface in FIG. 1). In addition, a body-internal partition portion **111** is formed between the body-internal passage **121** and the second introduction concave portion **13b**. Although the body-internal passage **121** is formed so as to be substantially in parallel with the rotation center axis **O** of the rotor **2**, the body-internal passage **121** need not be in a parallel in a strict sense, and it may be formed so as to be slightly angled to the radial direction or the circumferential direction with respect to the rotation center axis **O**.

The turning passage **122** is a concave portion that is recessed from one end side of the cover **20** in the axial direction (the right end side in FIG. 1) towards the other end side (the left end side in FIG. 1) and is formed so as to have a semicircular cross-sectional shape. A tip end portion of the body-internal partition portion **111** provided between the body-internal passage **121** and the second introduction concave portion **13b** is positioned at the vicinity of the center of the arc formed by an inner circumferential surface of the turning passage **122**.

The turning passage **122** has, as opening portions thereof, an inlet opening portion **122i** that faces an opening portion of the body-internal passage **121** and an outlet opening

portion **122o** that faces an opening portion of the second introduction concave portion **13b**. An end portion of the outlet opening portion **122o** on the drive shaft **1** side faces an opening portion of the cut-out portion **43** of the cover-side side plate **40**.

FIG. 6 is a plan view of the cover **20** and the cover-side side plate **40**, viewed from the VI direction in FIG. 4. As shown in FIG. 6, the communication passage **102** has an inlet portion **102a** that is provided in the first suction region **82a**, an exit portion **102b** that is provided in the second suction region **82c**, and two intermediate passages **102c** that are provided so as to extend between the inlet portion **102a** and the exit portion **102b**. The intermediate passages **102c** are each formed to have an arc shape so as to extend around the drive shaft **1**.

The cover **20** is provided with a partition portion **123** that partitions the turning passage **122** and the communication passage **102**. As shown in FIG. 1, the partition portion **123** extends from bottom portions of the turning passage **122** and the communication passage **102** (the left end portions in FIG. 1) to an opening plane of the cover **20** along the axial direction.

The flow of the working oil when the vane pump **100** is operated will be described with reference to FIGS. 1 and 6. Arrows shown in FIG. 6 show the directions of the flows of the working oil that is guided from the suction passage **101** to the communication passage **102** and the directions of the flows of the working oil flowing through the return passage **120**. In FIG. 6, arrows M1 to M3 show the flows of the working oil (also referred to as a main flow) flowing through the communication passage **102**, and arrows R1 and R2 show the flows of the working oil (also referred to as a returning flow) flowing through the return passage **120**. In the above, the arrows M3 and R2 show the flows flowing from the back side towards the front side along the straight direction orthogonal to the plane of the drawings, and the arrow R1 shows the flow flowing from the front side towards the back side along the direction orthogonal to the plane of the drawings.

As the drive shaft **1** is rotationally driven by a motive force from the driving device (not shown), such as an engine, etc., the rotor **2** is rotated in the direction shown by the arrow A in FIG. 2. As the rotor **2** is rotated, the pump chambers **6** positioned in the first suction region **82a** and the second suction region **82c** are expanded.

With such a configuration, as shown in FIG. 1, the working oil in the tank **60** is guided to the vane pump **100** through a passage **61**. The working oil that has been guided to the vane pump **100** is then sucked to the pump chambers **6** positioned in the first suction region **82a** through the first suction port **91** from the suction passage **101** of the body **10**.

In addition, the working oil that has been guided to the vane pump **100** also flows into the communication passage **102** from the suction passage **101** of the body **10**. As shown in FIG. 6, the working oil that has been guided from the suction passage **101** to the inlet portion **102a** of the communication passage **102** (see the arrow M1) is branched and guided to the two intermediate passages **102c**. The working oil that has been guided to the intermediate passages **102c** flows along the intermediate passages **102c** (see the arrow M2), and the flows join together at the exit portion **102b**. The working oil that has been guided to the exit portion **102b** is turned and flows along the axial direction and is sucked into the pump chambers **6** positioned in the second suction region **82c** via the second suction port **92** (see the arrow M3).

Furthermore, as shown in FIG. 1, the excessive oil that is not supplied to the fluid hydraulic apparatus **70** is guided to the body-internal passage **121**. The working oil that has been guided to the body-internal passage **121** flows towards the cover **20** along the axial direction and is introduced into the turning passage **122** in the cover **20** (see also the arrow R1 in FIG. 6). The direction of the flow of the working oil that has been introduced to the turning passage **122** is reversed along the inner circumferential surface of the arc shape. In other words, the direction of the flow of the working oil that has been introduced into the cover **20** from the body **10** is converted by the turning passage **122** to the opposite direction. The working oil that has been reversed by the turning passage **122** then flows towards the second introduction concave portion **13b** and the cut-out portion **43** of the cover-side side plate **40** from the outlet opening portion **122o** of the turning passage **122** (see also the arrow R2 in FIG. 6).

The working oil that has been guided to the second introduction concave portion **13b** flows between the second introduction concave portion **13b** and the outer circumferential surface of the cam ring **4** in the axial direction and is sucked into the pump chambers **6** positioned in the second suction region **82c** via the body-side side port **51** of the second suction port **92**. The working oil that has been guided to the cut-out portion **43** of the cover-side side plate **40** is then sucked into the pump chambers **6** positioned in the second suction region **82c** via the cover-side side port **52** of the second suction port **92**. In the above, a part of the working oil that has been guided to the cut-out portion **43** of the cover-side side plate **40** is redirected by hitting an axial direction end surface **4g** of the narrow-width portion **4f**, which is a plane of the cut-out portion **4d** of the cam ring **4** perpendicular to the axial direction, and is introduced to the pump chambers **6** from the outside of the pump chambers **6** in the radial direction.

As the rotor **2** is rotated, the pump chambers **6** positioned in the first discharge region **82b** and the second discharge region **82d** are contracted. Thus, the working oil in the pump chambers **6** is discharged to the high-pressure chamber **14** through the discharge ports **31** (see FIG. 2). The working oil that has been discharged to the high-pressure chamber **14** is then supplied to the external fluid hydraulic apparatus **70** through the discharge passage **62**.

Effects realized by providing the above-described turning passage **122** will be described with reference to FIGS. 7a and 7b in comparison with a comparative example. FIG. 7A is a schematic side-sectional view of the vane pump **100** according to this embodiment and shows the flow of the working oil (the main flow) that is guided from the suction passage **101** to the cartridge **9** and the flow of the working oil (the returning flow) that is guided from the return passage **120** to the cartridge **9**. FIG. 7B is the schematic side-sectional view of a vane pump **100A** according to the comparative example of this embodiment and shows the flow of the working oil (the main flow) that is guided from the suction passage **101** to the cartridge **9** and the flow of the working oil (the returning flow) that is guided from a return passage **120A** to the cartridge **9**. In the figures, the flow of the working oil (the main flow) that is introduced to the suction passage **101** is shown schematically by open arrows, and the flow of the working oil (the returning flow) that is introduced to the return passage **120, 120A** is shown schematically by solid arrows.

As shown in FIG. 7B, in the vane pump **100A** according to the comparative example of this embodiment, the return passage **120A** is provided in a straight line towards the

11

second introduction concave portion **13b** from an inlet provided on one end of a body **10A** in the axial direction (the lower end in the figure), and the turning passage **122** that is described in this embodiment is not provided. Therefore, most of the excessive oil that has been guided to the return passage **120A** enters the communication passage **102** from the second introduction concave portion **13b**.

The direction of the flow of the excessive oil (the returning flow) that is guided from the return passage **120A** to the second introduction concave portion **13b** is in the opposite direction from the direction of the flow of the working oil (the main flow) directed from the suction passage **101** towards the second introduction concave portion **13b** via the communication passage **102**. Therefore, the flow of the working oil to be sucked into the second suction port **92** from the suction passage **101** via the communication passage **102** is inhibited, thus causing a pressure loss.

In addition, remaining excessive oil from the suction at the second suction port **92** forms a counter flow flowing towards the first suction port **91** through the communication passage **102** and inhibits the suction of the flow of the working oil at the first suction port **91** from the suction passage **101**, and therefore, there is a concern that the suction property from the first suction port **91** to the pump chamber **6** is deteriorated. Therefore, with the comparative example of this embodiment, there is a concern that the suction property of the vane pump **100A** is lowered due to the excessive oil guided by the return passage **120A**.

In contrast, in the vane pump **100** according to this embodiment, as shown in FIG. 7A, the excessive oil that has been guided to the body-internal passage **121** of the return passage **120** is reversed by about 180° by the turning passage **122**. With such a configuration, it is possible to substantially match the direction of the flow of the working oil (the main flow) directed from the communication passage **102** towards the second suction port **92** and the direction of the flow of the excessive oil (the returning flow) that has been reversed by the turning passage **122** and directed towards the second suction port **92**. Therefore, the working oil that has been guided to the second suction port **92** from the suction passage **101** via the communication passage **102** and the excessive oil that has been guided to the second suction port **92** from the return passage **120** are both sucked into the pump chambers **6** in an effective manner. Therefore, because the inhibition caused by the returning flow to the flow of the working oil that is to be sucked into the second suction port **92** from the suction passage **101** via the communication passage **102** is suppressed, the pressure loss is reduced compared with the above-described comparative example.

Note that the cover **20** is provided with the partition portion **123** for partitioning the turning passage **122** and the communication passage **102**, and therefore, it is possible to effectively suppress inflow of the excessive oil to the communication passage **102**. Therefore, in the cover **20**, it is possible to effectively suppress inhibition caused by the excessive oil, which is guided by the turning passage **122**, to the flow of the working oil (the main flow) directed to the second suction port **92** from the suction passage **101** via the communication passage **102**.

In addition, in this embodiment, each of the cover-side side ports **52** has the cut-out portion **43** that opens to the outer circumferential surface and penetrates through between both end surfaces, and so, the opening of the cover-side side port **52** is formed so as to be larger than the opening of the body-side side port **51**. Therefore, it is possible to introduce most of the excessive oil into the pump chambers **6** from the cover-side side port **52** and to introduce

12

the working oil that is guided by the communication passage **102** to the pump chambers **6** from the side of the pump chambers **6**. Therefore, it is possible to increase the suction amount into the pump chambers **6** via the second suction port **92**. In other words, it is possible to improve the suction property of the pump chambers **6** positioned in the second suction region **82c**.

Furthermore, in this embodiment, because the excessive oil is efficiently sucked into the pump chambers **6** via the second suction port **92**, the formation of the counter flow of the excessive oil directed towards the first suction port **91** via the communication passage **102** is suppressed. Thus, compared with the comparative example, the decrease in the suction property of the pump chambers **6** positioned in the first suction region **82a** is also suppressed.

As described above, in this embodiment, it is possible to suppress the decrease in the suction property of the vane pump **100** due to the excessive oil guided by the return passage **120**. In other words, according to this embodiment, compared with the comparative example, it is possible to improve the suction property of the vane pump **100**.

In the above, the turning passage **122** of the cover **20** according to this embodiment can be formed together with the communication passage **102**, etc. by a molding processing, and so, compared with a cover **20A** in the comparative example, there is no increase in processing steps.

According to the above-described embodiment, following operational advantages are afforded.

The return passage **120** has the body-internal passage **121** through which the excessive oil flows along the rotation center axis **O** direction of the rotor **2** at the outer side of the cam ring **4** in the radial direction and the turning passage **122** that causes the excessive oil that is guided through the body-internal passage **121** to be reversed towards the second suction port **92**. In other words, in this embodiment, it is possible to guide the excessive oil to the second suction port **92** by reversing the excessive oil by the turning passage **122** provided in the cover **20**. By doing so, the inhibition of the flow of the working oil directed from the suction passage **101** towards the first suction port **91** and the inhibition of the flow of the working oil directed from the suction passage **101** towards the second suction port **92** via the communication passage **102**, which are both caused by the excessive oil, are suppressed. As a result, it is possible to improve the suction property of the vane pump **100**.

The following modifications also fall within the scope of the present invention, and it is also possible to combine the configurations shown in the modifications with the configurations described in the above embodiment, or to combine the configurations described in the following different modifications.

In the above-mentioned embodiment, although a description has been given of an example in which the inlet **120i** of the return passage **120** is formed at the one end surface of the body **10** in the axial direction, the present invention is not limited to this configuration. For example, as in a first modification shown in FIG. 8, an inlet **220i** of a return passage **220** may be formed at the outer circumferential surface of the body **10**. In this first modification, a body-internal passage **221** of the return passage **220** has an axial direction passage **221a** that is connected to the turning passage **122** and extends in the axial direction and an inlet passage **221b** that extends from the inlet **220i** of the return passage **220** and is connected to the axial direction passage **221a**. Similarly to the body-internal passage **121** in the above-mentioned embodiment, the axial direction passage **221a** is formed such that the excessive fluid flows along the

rotation center axis O direction of the rotor 2 at the outer side of the cam ring 4 in the radial direction. Although the axial direction passage 221a is formed so as to be substantially in parallel with the rotation center axis O of the rotor 2, the axial direction passage 221a need not be in a parallel in a strict sense, and it may be formed so as to be slightly angled in the radial direction or the circumferential direction with respect to the rotation center axis O. The operational advantages similar to those in the above-mentioned embodiment are also afforded in such a first modification.

In addition, in the above-mentioned embodiment, although a description has been given of an example in which the cover 20 is provided with the partition portion 123 for partitioning the turning passage 122 and the communication passage 102, the present invention is not limited to this configuration. As in a second modification shown in FIG. 9, the turning passage 122 may be in communication with the communication passage 102 in the cover 20. Any configuration may be employed so long as the working oil that has been guided from the body-internal passage 121 to the turning passage 122 of the cover 20 can be at least reversed towards the second suction port 92 by the turning passage 122. The operational advantages similar to those in the above-mentioned embodiment are also afforded in such a second modification.

In addition, in the above-mentioned embodiment, although a description has been given of an example in which the turning passage 122 and the communication passage 102 are provided in the cover 20, the present invention is not limited to this configuration. As in a third modification shown in FIG. 10, the turning passage 122, the communication passage 102, and the partition portion 123 that partitions these passages may be provided in the body 10. In this case, the annular high-pressure chamber 14 is provided in the cover 20, and the inlet 120i of the return passage 120 is provided in the cover 20. In addition, in this case, the cut-out portions 43 forming the side port are formed in the body-side side plate 30 serving as the plate member provided between the communication passage 102 and the pump chamber 6, and not in the cover-side side plate 40 provided between the cover 20 and the cam ring 4. In other words, in the third modification, the side port to which the excessive fluid is guided by the turning passage 122 is formed in the body-side side plate 30. The operational advantages similar to those in the above-mentioned embodiment are also afforded in such a third modification.

In addition, in the above-mentioned embodiment, although a description has been given of an example in which the cut-out portions 4c and 4d are formed in the cam ring 4, the present invention is not limited to this configuration. Either one or both of the cut-out portions 4c and 4d of the cam ring 4 may be omitted. In other words, the body-side side ports 51 may be formed only by the recessed portions 33 of the body-side side plate 30, or the cover-side side ports 52 may be formed only by the cut-out portions 43 of the cover-side side plate 40.

In addition, in the above-mentioned embodiment, although a description has been given of an example in which the turning passage 122 is formed so as to have the semicircular cross-sectional shape, the present invention is not limited to this configuration. The turning passage 122 may be formed to have a various shapes that can reverse the working oil that has been guided by the body-internal passage 121 towards the second suction port 92. For example, the turning passage 122 may be formed such that its cross section becomes a triangular shape. In addition, by adjusting an opening angle, an orientation, and a shape of the

turning passage 122, it is possible to easily adjust the direction of the flow of the excessive oil.

The configurations, operations, and effects of the embodiment of the present invention configured as described above 5 will be collectively described.

The vane pump 100 has: the rotor 2 configured to be rotationally driven; the plurality of vanes 3 provided so as to be capable of freely reciprocating in the radial direction with respect to the rotor 2; the cam ring 4 having the inner 10 circumference cam face 4a on which the tip end portions 3a of the plurality of vanes 3 slide with the rotation of the rotor 2; the body 10 having the accommodating concave portion 10b for accommodating the rotor 2 and the cam ring 4; the cover 20 attached to the body 10 to close the accommodating concave portion 10b; the pump chambers 6 formed by the rotor 2, the cam ring 4, and the adjacent vanes 3; the first suction port 91 configured to guide the working fluid to the pump chambers 6, the working fluid being guided by the suction passage 101 provided in the body 10; the second suction port 92 configured to guide the working fluid to the pump chambers 6, the working fluid being guided from the suction passage 101 through the communication passage 20 15 20 25 30 35 40 45 50 55 60 65 70 75 80 85 90 95 100 105 10b 110 115 120 125 130 135 140 145 150 155 160 165 170 175 180 185 190 195 200 205 210 215 220 225 230 235 240 245 250 255 260 15

configured to partition the turning passage 122 and the communication passage 102 in the rotation center axis O direction of the rotor 2.

With this configuration, it is possible to effectively suppress the inhibition of the flow of the working fluid directed towards the second suction port 92 from the suction passage 101 via the communication passage 102 caused by the excessive fluid guided through the turning passage 122.

Embodiments of the present invention were described above, but the above embodiments are merely examples of applications of the present invention, and the technical scope of the present invention is not limited to the specific constitutions of the above embodiments.

This application claims priority based on Japanese Patent Application No. 2019-078491 filed with the Japan Patent Office on Apr. 17, 2019, the entire contents of which are incorporated into this specification by reference.

The invention claimed is:

1. A vane pump comprising:

a rotor configured to be rotationally driven; a plurality of vanes provided so as to be capable of freely reciprocating in a radial direction with respect to the rotor;

a cam ring having an inner circumference cam face on which tip end portions of the plurality of vanes slide with rotation of the rotor;

a body having an accommodating portion for accommodating the rotor and the cam ring;

a cover attached to the body to close the accommodating portion;

pump chambers formed by the rotor, the cam ring, and the adjacent vanes;

a first suction port configured to guide working fluid to the pump chambers, the working fluid being guided by a suction passage provided in the body;

a second suction port configured to guide the working fluid to the pump chambers, the working fluid being guided from the suction passage through a communication passage provided in the cover or the body; and

a return passage to which excessive fluid is guided, the excessive fluid being derived from the working fluid discharged from the pump chambers, wherein the return passage has:

an axial direction passage through which only the excessive fluid flows along a rotation-axis direction of the rotor at an outer side of the cam ring in a radial direction; and

a turning passage configured to reverse the excessive fluid towards the second suction port, only the excessive fluid being guided to the turning passage through the axial direction passage, and the axial direction passage and the turning passage are provided separately from the suction passage and the communication passage.

2. The vane pump according to claim 1, further comprising:

a plate member arranged between the communication passage and the pump chambers, wherein

the plate member is provided with a cut-out portion, the cut-out portion opening at an outer circumferential surface of the plate member, and the cut-out portion penetrating through between both end surfaces of the plate member, and

the second suction port has a side port formed by the cut-out portion of the plate member, and

16

the turning passage is configured to reverse the working fluid towards the side port, the working fluid being guided by the axial direction passage.

3. The vane pump according to claim 1, wherein a partition portion is provided between the turning passage and the communication passage, the partition portion being configured to partition the turning passage and the communication passage in the rotation-axis direction.

4. A vane pump, comprising:
a rotor configured to be rotationally driven; a plurality of vanes provided so as to be capable of freely reciprocating in a radial direction with respect to the rotor;

a cam ring having an inner circumference cam face on which tip end portions of the plurality of vanes slide with rotation of the rotor;

a body having an accommodating portion for accommodating the rotor and the cam ring;

a cover attached to the body to close the accommodating portion;

pump chambers formed by the rotor, the cam ring, and the adjacent vanes;

a first suction port configured to guide working fluid to the pump chambers, the working fluid being guided by a suction passage provided in the body;

a second suction port configured to guide the working fluid to the pump chambers, the working fluid being guided from the suction passage through a communication passage provided in the cover or the body;

a return passage to which excessive fluid is guided, the excessive fluid being derived from the working fluid discharged from the pump chambers; and

a plate member arranged between the communication passage and the pump chambers, wherein the return passage has:

an axial direction passage through which the excessive fluid flows along a rotation-axis direction of the rotor at an outer side of the cam ring in a radial direction; and

a turning passage configured to reverse the excessive fluid towards the second suction port, the excessive fluid being guided through the axial direction passage,

the plate member is provided with a cut-out portion, the cut-out portion opening at an outer circumferential surface of the plate member, and the cut-out portion penetrating through between both end surfaces of the plate member,

the second suction port has a side port formed by the cut-out portion of the plate member, and

the turning passage is configured to reverse the working fluid towards the side port, the working fluid being guided by the axial direction passage.

5. A vane pump, comprising:
a rotor configured to be rotationally driven; a plurality of vanes provided so as to be capable of freely reciprocating in a radial direction with respect to the rotor;

a cam ring having an inner circumference cam face on which tip end portions of the plurality of vanes slide with rotation of the rotor;

a body having an accommodating portion for accommodating the rotor and the cam ring;

a cover attached to the body to close the accommodating portion;

- pump chambers formed by the rotor, the cam ring, and the adjacent vanes;
- a first suction port configured to guide working fluid to the pump chambers, the working fluid being guided by a suction passage provided in the body; 5
- a second suction port configured to guide the working fluid to the pump chambers, the working fluid being guided from the suction passage through a communication passage provided in the cover or the body; and
- a return passage to which excessive fluid is guided, the 10 excessive fluid being derived from the working fluid discharged from the pump chambers, wherein the return passage has:
- an axial direction passage through which the excessive fluid flows along a rotation-axis direction of the rotor 15 at an outer side of the cam ring in a radial direction; and
- a turning passage configured to reverse the excessive fluid towards the second suction port, the excessive fluid being guided through the axial direction passage, and
- a partition portion is provided between the turning passage and the communication passage, the partition portion being configured to partition the turning passage and the communication passage in the rotation- 20 axis direction, and
- a partition portion is provided between the turning passage and the communication passage, the partition portion being configured to partition the turning passage and the communication passage in the rotation- 25 axis direction.
